UNITED STATES PATENT OFFICE.

ALLEN CONKLING, OF CHICAGO, ILLINOIS.

RETURN-FEED DEVICE.

SPECIFICATION forming part of Letters Patent No. 633,988, dated October 3, 1899.

Application filed June 6, 1899. Serial No. 719,584. (No model.)

To all whom it may concern:

Be it known that I, ALLEN CONKLING, a citizen of the United States, residing at Chicago, in the county of Cook, State of Illinois, have 5 invented certain new and useful Improvements in Return-Feed Devices, of which the following is a specification, reference being had therein to the accompanying drawings.

This invention relates to feeding mechanism intended to be used in connection with machines which in operating upon material carry it or cause it to pass through the principal operative elements—such as the rollers of rolling, pressing, or ironing machines—and 15 although primarily intended for use on or application to machines for ironing apparel articles it is also equally as useful in any machine to or into which the operator feeds the goods by hand, so that by this invention articles after being passed once through the machine may be either surely received and retained upon the opposite side of the machine or may be automatically directed toward the operator at the front of the machine for a second operation, and this at the will of the operator and without the necessity of leaving his position at the front of the machine.

The invention consists of a return-feed device having a reciprocatory and tilting movement, and particularly of such a device adapted at will to receive goods from and in line with the point of delivery of the operative elements of a machine to hold or to return them.

35 The invention has for its object to mount a shelf for movement toward and from the operative elements of a machine, so that the goods may be received by said shelf, or by moving the shelf away from the elements the goods will pass beneath the same.

40 A further object of the invention is to mount this shelf so that the same may be tilted for the purposes of discharging the goods received thereon into a conducting-receptacle.

45 A further object of the invention is to provide a very simple and efficient construction of parts by which the preliminary movement of the shelf will be in a substantially horizontal plane and in the subsequent movement 50 the receiving edge of the shelf will be tilted downwardly.

The invention has also for an object to pro-

vide a tiltable shelf closely adjacent to the operative elements of a machine in order to receive goods directly therefrom and by the 55 tilting of the shelf deliver said goods to a conducting-receptacle, whereby an operator at the front of the machine can both feed the machine and receive the finished work at a single point, from which position he can also 60 control both the horizontal and tilting movements of the shelf.

Other objects and advantages of the invention will hereinafter appear in the following description, and the novel features thereof 65 will be particularly pointed out in the appended claims.

In the drawings, Figure 1 is a vertical section through a machine provided with my invention. Fig. 2 is a rear elevation thereof, 70 and Fig. 3 is a detail elevation of one of the guiding-brackets.

Like letters of reference indicate like parts throughout the several figures of the drawings.

75 The letter A designates a suitable framework, which may be of any desired character, as it will be obvious that the return-feed device is capable of application to any class of machine embodying the operative elements—80 such, for instance, as a pair of rollers B and B'. (Shown in the drawings.) The application of the invention is not, however, confined to the ironing-machine herein shown, as this machine is selected merely for illustrative purposes in demonstrating the application 85 of the invention. In the present illustration the roller B is a heated ironing-roller, while the roller B' is a clothed roller, and the ironing operation is performed by said rollers 90 so that the goods are delivered from the same onto the shelf or table C, which constitutes the receiving element of this invention. This shelf or table may be of any desired size or configuration, and if found convenient the 95 front edge C is reduced in thickness to act as a doffer-blade adjacent to one of the operative elements—for instance, the roller B'. The table is moved to and from the operative elements by means of an oscillating lever or levers D, which are secured to a rotatable shaft D' by means of a set-screw D², to which lever a rock-arm D³ is also secured and connected by a link D⁴ with a treadle mechanism D⁵.

This treadle is provided with an operating foot or step D⁶ for its movement in one direction and at its upper end with a weight D⁷ to return the same to its initial or normal position. It may here be stated, however, that the invention is not confined to the particular means for operating the shelf, as the same are merely selected for the purpose of illustration, and any suitable mechanical connection may be substituted to perform these functions and to operate the oscillating lever D.

The shelf C is provided with a guide-pin C², projecting from its side, which travels in a way E, formed in a bracket E', carried by a fixed part of the machine. This guide or way has a portion e thereof disposed in a slightly-descending horizontal plane and a portion e' extended into a vertical plane, the two portions being connected together by a curved or segmental portion e³. This bracket is particularly described for the purposes to be hereinafter set forth, and the invention is not confined to the specific form of bracket, as any guiding element may be substituted therefor to perform these functions of the invention.

Beneath the operative elements of the machine a conducting-receptacle E² is located, which may be composed of side pieces E³, connected together by a suitable bottom E⁴, and at the front of this receptacle a table or shelf E⁵ is provided for the obvious uses of the operator. This conducting-receptacle is suitably supported by brackets E⁶, mounted upon a cross-rod A', connecting the opposite sides of the machine-frame, and upon the shaft D', and the elements which have been described as carried by the frame and connected with the shelf may be disposed upon opposite sides of said shelf, and thus duplicated.

For the purpose of demonstrating the operation of the table C its functions and advantages in practical use upon an ironing-machine will be clearly stated, and more particularly the two separate functions of which it is capable. The movement of the table to the ironing-rollers permits small articles, such as collars and cuffs, to be received upon the shelf, and by partially depressing the treadle and moving the shelf slightly backward other articles will pass the edge C' of the shelf and drop to the conducting-receptacle, or a reversed operation may be conducted, if so desired. When an article is to be reironed and it is desired to return the same so that the operator can reach it from the front of the machine, the treadle is completely depressed, which, after moving the table out of possible contact with the clothed roller, lowers the inner end of the table by the pins C² traveling in the vertical portion of the path E, thus permitting the goods to fall into the receiving-receptacle, from which they can readily be reached by the operator at the front of the machine.

It is an important feature in this class of return-feeds to bring the shelf or table into

close relation to the operative element or roller in order that small articles may at once pass upon the shelf, the edge of which may act as a doffer-blade. For this reason the preliminary horizontal movement is a highly-important feature of construction. Furthermore, if the goods ironed are permitted to follow the configuration of the rollers they will be delivered in a curved or curled condition. This is prevented by the straight or horizontal floor of the shelf, which receives the goods in a horizontal plane. It will be obvious that the machine is capable of operation by a single operator when this return-feed device is applied thereto, and, furthermore, that the location and movement of the shelf effectively remove the ironed goods from intimate contact with or close proximity to the clothed roller, which emits steam or vapor injurious to the finished surface of the goods. Furthermore, more or less moisture is imparted to the goods if they be conducted downwardly in intimate contact with the clothed roller.

From the foregoing it is obvious that the invention may be applied to any class of machines in which goods are adapted to be delivered directly from the operative elements and that numerous changes may be made in the structure and configuration of the several parts hereinbefore described without departing from the spirit of the invention as defined by the appended claims.

Having described my invention, what I claim as new, and desire to secure by Letters Patent, is—

1. A return-feed device comprising a shelf mounted for reciprocatory movement toward and from and in line with the point of delivery of the operative elements of a machine and adapted to receive and retain goods when nearest said elements; substantially as specified.
2. A return-feed device comprising a shelf mounted for movement toward and from the operative elements of a machine and means for tilting said shelf; substantially as specified.
3. A return-feed device comprising a shelf mounted for movement toward and from the operative elements of a machine, means for tilting said shelf, and a conducting-receptacle adapted to receive goods from said shelf; substantially as specified.
4. A return-feed device comprising a shelf mounted for a preliminary movement tangentially from the operative elements of a machine and a subsequent movement at an angle to the line of said tangential movement, and means for moving said shelf; substantially as specified.
5. A return-feed device comprising a movable shelf, a bracket provided with a path or track disposed in two planes and adapted to coöperate with said shelf, and means for moving said shelf; substantially as specified.
6. A return-feed device comprising a movable shelf, a bracket provided with a path or

- track disposed in two planes and adapted to coöperate with said shelf, and an oscillating arm pivoted to said shelf; substantially as specified.
- 5 7. A return-feed device comprising a movable shelf, a bracket provided with a path or track disposed in two planes and adapted to coöperate with said shelf, an oscillating arm pivoted to said shelf, and a treadle connection 10 to actuate said arm; substantially as specified.
8. A return-feed device comprising a movable shelf, a bracket provided with a path or track disposed in two planes and adapted to coöperate with said shelf, an oscillating arm pivoted to said shelf, and a curved conducting-receptacle adapted to receive goods from said shelf when in an inclined position; substantially as specified.
- 15 20 9. A return-feed device comprising a shelf provided with a pin, a bracket provided with an upwardly-curved guide-slot, an oscillating arm pivotally connected to said shelf, means for actuating said arm, and a conducting-receptacle adapted to receive goods from said shelf; substantially as specified.
10. The combination with a pair of rollers, of a horizontally-disposed receiving-shelf extending closely adjacent to the periphery of one of said rollers, a projecting pin from the 30 side of said shelf, a bracket provided with an upwardly-curved guide-slot for said pin, an oscillating arm pivotally connected to said shelf, means for oscillating said arm, and a conducting-receptacle beneath said rollers 35 and adapted to receive goods from said shelf when tilted; substantially as specified.

In testimony whereof I affix my signature in presence of two witnesses.

ALLEN CONKLING.
